UNITED STATES PATENT OFFICE.

OZELLO R. HUNT, OF KENOSHA, WISCONSIN, ASSIGNOR TO THE SIMMONS MANUFACTURING COMPANY, OF KENOSHA, WISCONSIN, A CORPORATION OF WISCONSIN.

SPRING-BOTTOM.

No. 799,853.

Specification of Letters Patent.

Patented Sept. 19, 1905.

Application filed April 27, 1905. Serial No. 257,637.

To all whom it may concern:

Be it known that I, OZELLO R. HUNT, a citizen of the United States, residing at Kenosha, in the county of Kenosha and State of Wisconsin, have invented a new and useful Spring-Bottom, of which the following is a specification.

My invention pertains particularly to spring-bottoms for beds; and my primary object is to provide a bottom with improved means for supporting the fabric.

My invention is illustrated in its preferred embodiment in the accompanying drawings, in which—

15 Figure 1 represents a broken bottom plan view of my improved spring bed-bottom; Fig. 2, an enlarged broken section taken as indicated at line 2 of Fig. 1; Fig. 3, a perspective view of parts of a transverse supporting member employed; Fig. 4, an enlarged sectional view of an elastic cable employed, taken as indicated at line 4 of Fig. 1; Fig. 5, a broken perspective view of a clip employed; Fig. 6, a broken section taken as indicated at line 6 25 of Fig. 1, and Fig. 7 a view of a modified transverse supporting member.

In the construction shown, A represents a frame, B a woven-wire fabric of known construction, and C a fabric-support of improved 30 construction.

The frame in the form shown comprises side members a, end members a', rigidly secured to the side members, and fabric-clamping members a², joined by spikes a³ and clips 35 a⁴ to the members a'. The clips have nail-receiving perforations, as shown in Fig. 5, and are connected by nails a⁵ to the ends of the members a' a².

The fabric B comprises the usual intertwined 40 longitudinal single spirals b, Fig. 2, and stronger several-ply spirals b' at the longitudinal edges and at suitable intervals between said edges.

The fabric-support C comprises elastic 45 flexible cables c, having their extremities clamped (with the ends of the fabric) between the members a' a², and a plurality of cross members c' of adjustable length joining the members c at their central portions. Ordinarily 50 three of the cross members spaced about ten inches apart, with the central one at

the transverse axis of the bed, are sufficient and desirable. Each elastic cable c preferably comprises an inner comparatively closely wound spiral c² and a plurality of intertwined 55 spirals c³, sheathing the spiral c², the whole being strong and resilient, but yielding in a desirable degree. Each cross member c' comprises a rod c⁴, provided at its ends with hooks c⁵, sheet-metal loops c⁶, each formed with a 60 passage c⁷ for the cable and with superposed legs c⁸, provided with perforations c⁹, and clips c¹⁰, each embracing an end portion of the 65 rod and the members c' of the corresponding loop c⁶. The clips are shiftable longitudinally 70 of the rods to enable adjustment of the rods to be effected.

In the preferred method of applying the support C the cables c are stretched with small tension beneath the longitudinal margins 75 of the fabric or wire mattress and have their ends clamped between the members a' a² of the frame. The rods c⁴ are then threaded transversely through the central portion of the fabric, leaving the end portions of the 75 rods unthreaded, as shown in Fig. 2. The loops c⁶ are then applied to the cables, the hooks c⁵ caused to engage proper perforations in the members c', according to tension 80 desired, and the clips c¹⁰ (assumed to be on the rods) slipped into place. Preferably the central member c' is somewhat shorter than the other two members, and in adjusting the tension the cables c are drawn upon at their central portions to form obtuse angles, as shown 85 in Fig. 1. The construction results naturally in a slight roll or downward wave of the lateral margins of the fabric, as indicated at d in Fig. 2, enabling the edge of the bed to be 90 comfortably as a seat.

In the modification shown in Fig. 7 a rod c¹¹ serves as a substitute for the transverse member c', said rod c¹¹ having at its ends eyes c¹² (one shown) for receiving the cables c. One of the eyes of each rod is preparatory formed or partially formed, and after the rod is threaded through the fabric the other eye is formed about the cable. In this construction the fabric holds the cross members properly spaced under any strain which 95 may be placed upon the structure.

The construction is simple and cheap and

provides for ready adjustment of tension at any time, and experience has proved it to be exceedingly comfortable and durable.

What I regard as new, and desire to secure 5 by Letters Patent, is—

1. In a spring-bottom, the combination with a frame and a fabric comprising wire spirals connected with the ends of the frame, of a fabric-support, comprising cables arranged 10 beneath the lateral margins of the fabric and joining the ends of the frame, and a plurality of suitably-spaced transverse members joining the intermediate portions of the cables, each transverse member formed with a wire 15 threaded through the spirals of the fabric, for the purpose set forth.

2. In a spring-bottom, the combination with a frame and a fabric attached at its ends to the ends of the frame, of a fabric-support, comprising a pair of longitudinal cables beneath 20 the lateral margins of the fabric, and a transverse connecting member connecting and deflecting the central portions of the cables and

comprising a rod having hooks at its ends, and loops receiving the cables and provided 25 with perforations receiving said hooks, for the purpose set forth.

3. In a spring-bottom, the combination with a frame and a fabric comprising wire spirals connected with the ends of the frame, of a 30 fabric-support comprising cables arranged beneath the lateral margins of the fabric and joining the ends of the frame, and a plurality of suitably-spaced transverse members joining the intermediate portions of the cables, each transverse member comprising a rod provided at its ends with hooks, loops receiving 35 the cables and provided with a plurality of perforations for receiving said hooks, for adjustment purposes, and clips connecting the rods and loops adjacent to the hooks, for the purpose set forth.

OZELLO R. HUNT.
